SURVEYING INSTRUMENT

Adolph Langsner, Chicago, Ill., assignor to Eugene Dietzgen Company, Chicago, Ill., a corporation of Delaware

Application March 16, 1935, Serial No. 11,525

8 Claims. (Cl. 33—67)

My invention relates in general to measuring instruments and has more particular reference to alidades and similar precision instruments for use in surveying.

5 An important object is to provide an adjustable support for a telescope or other sighting device providing an alidade wherein the telescope may be adjusted in various sighted positions by adjusting mechanism carried by and forming a part 10 of the support wherein the support and adjusting means are designed to co-operate for the exclusion of dirt and other foreign matter to the adjusting mechanism.

15 A further object is to simplify and reduce the number of operating parts in an alidade while, at the same time, configuring the parts which are retained in order to enhance the attractive appearance of the instrument, the parts being formed to facilitate assembly thereof.

20 Another important object is to provide a support for a sighting device of the character mentioned including a tilting frame, on which the device is mounted, and tangent screw means for adjusting the tilting frame on the support, the 25 arrangement of a housing or enclosure on the support and into which an end of an arm on the tilting frame may extend in position to co-operate with tangent adjusting screws carried by the support whereby the adjusting screws and the arm of the tilting frame are hidden within the enclosure 30 and protected from dirt and other foreign matter while a neat and pleasing appearance is imparted to the construction.

Another important object is to provide a support for a sighting device, including a frame on 35 which the device is tiltably mounted, the frame being formed with a chamber having an opening in which extends an arm connected with the device wherein the frame carries adjusting means 40 operatively associated with the arm within the chamber whereby the adjusting means is enclosed and protected against mechanical damage and guarded against dust, moisture and other deteriorating elements.

45 Another important object is to provide, preferably in conjunction with the adjusting arm of the support, cooperating scale elements enclosed in a housing and thus guarded against the deleterious effects of dust, moisture and the like, whereby a more serviceable and sightly instrument is provided.

50 Another important object is to provide an improved scale cover and scale construction for tiltably mounted sighting devices whereby the scales are enclosed and protected against mechanical

damage by external forces and against the entrance of foreign matter, said structure serving to provide a more attractive instrument at reduced cost.

5 Numerous other objects and advantages of the invention will be apparent from the following description, which, taken in connection with the accompanying drawings, discloses preferred embodiments of my invention.

Referring to the drawings:

10 Figure 1 is a side elevation of an instrument embodying the features of my present invention;

Figure 2 is an enlarged sectional view taken substantially along the line 2—2 in Figure 1;

Figure 3 is a sectional view taken substantially 15 along the line 3—3 in Figure 1;

Figure 4 is a sectional view taken substantially along the line 4—4 in Figure 3; and

Figure 5 is a sectional view taken substantially 20 along the line 5—5 in Figure 4.

To illustrate my invention, I have shown, on the drawings, a measuring instrument comprising a sighting device 11 and support means for tiltably carrying the sighting device in operative position. The assembly also includes manually 25 operable devices carried on the support for adjusting the angularity of the sighting device, and means for determining a variety of data dependent upon the tilted position of the telescope on the support.

30 The instrument, which I have illustrated, comprises an alidade, although it is obvious that many features of the present invention are not necessarily restricted to this particular type of surveying instrument. The sighting device 11 35 preferably comprises a telescope supported in a sleeve-like frame 13 having projecting axles 15 carried in bearings 17 formed in spaced upstanding arms 19 of a support frame 21. The frame 21 has a base 23 mounted on a pedestal 25 which, in 40 turn, is supported on a base 27 comprising an elongated strip, at least one edge of which is formed as a straight edge 29, the parts being arranged so that the longitudinal axis of the telescope lies at all times in the medial plane of the 45 assembly and parallel with the straight edge 29. The frame 13 and axles 15 provide for the tilting of the telescope about an axis at right angles to the plane in which the axis of the telescope extends. The base 27 also carries a compass 31. 50

The pedestal 25 preferably comprises a tubular element formed with a flanged base 35, which is or may be secured preferably on the mid-portion of the base 27 in any suitable fashion as by means of the fastening studs 37. The pedestal 55

extends upwardly of the base and tapers inwardly toward its upper end, said pedestal having a flanged portion 39 at said upper end adapted to receive and form a support for the base 23 of the frame 21, which is secured to the pedestal in any suitable fashion as by means of the fastening studs 41. The upstanding arms 19 are preferably of frame-like construction comprising spaced legs 43 interconnecting at their upper 10 ends to form the lower half of the bearing 17, said legs 43 carrying a cap 45 providing the upper half of the bearing 17.

The lower ends of the legs are connected to the base of the frame 21 in spaced relationship 15 and walls 47 are formed extending between the lower portions of said legs and forming with said legs and the base of the frame an enclosed chamber 49 containing an elongated slot 51. One of the axles 15 of the frame 13 projects outwardly 20 of its bearing and is formed with a head 53 adapted to receive a clamping element 55 comprising a split collar 57 embracing the head 53 and an arm 59 extending radially of said split collar and having an end extending through the 25 slot 51 and into one of the chambers 49, the end of the arm within the chamber being formed with a disk 61. The split collar 57 is held on the head 53 in any suitable fashion as by means of the washer 63 and the holding screw 65. Clamp 30 means 67, comprising a threaded shaft interconnecting the split portions of the collar 57 and a manually operable head 69 for tightening and loosening the screw, is provided for clamping the collar 57 on the head 53 so that the arm 59 may 35 be made fast with the axle 15.

The other axle of the frame projects outwardly of the bearing in which it is journaled and is formed to provide a head having a portion 71, on which is journaled a spider-like element 73 of 40 semicircular cross-sectional configuration and having a central arm 75 having a projecting leg 77 extending through a slot 51 into one of the chambers 49, the end of said projecting arm 79 being formed as a disk 81 similar to the disk-like end 61 of the clamp arm 59. The arms 59 and 79 extend in different chambers 49 on opposite sides of the instrument.

The axle portion 71 has an extension 83 carrying a segmental spider 85, which extends adjacent 50 and in front of the spider 75. The segmental spider 85 is secured to and made fast in any suitable fashion, as by the fastening studs 87, to the axle. The spider 85 consequently is fast with the frame 13 and will turn with the telescope or 55 sighting device. The spider 75, however, is loose on the axle portion 71 and may consequently be held stationarily with respect to the support pedestal, by means of the arm 79. The telescope may be rotated freely by hand by loosening the nut 69 in order to release the clamp 57. After the telescope has been sighted in a rough way, the nut 69 may be tightened to clamp the arm 59 to the telescope so that further accurate adjustment of the telescope may be accomplished through said arm. 60 In order to accurately level the spider 75 and also to accurately adjust the telescope in sighting the same, the pedestal is provided with tangent screw 65 adjusting means 50 in position to co-operate with the ends of the arms 59 and 79 within the chambers 49, there being separate adjusting means for 70 each arm.

The tangent adjusting means 50 are preferably of like construction comprising a threaded stem 52 and a backing pin 54 having bearing portions 75 adapted to engage opposite sides of the disk-like

ends 61 and 81. The stem 52 is threaded in a sleeve-like support collar 56, one end of which is threaded as at 58 in an opening formed in the frame 23 at one end of the opening 49 so that the sleeve-like support element 56 extends outwardly of the frame in substantial alignment with the chamber 49. The stem 52 extends in the sleeve 56 and has an end disposed within the chamber 49 in position to engage one side of the disk 61 or 81 with which it is associated. The opposite end of the stem projects outwardly of the outer end of the sleeve 56 and is fitted with a knob 60 by means of which the stem 52 may be turned in the sleeve and advanced or retarded. The turning knob 60 is preferably formed externally with spherical surfaces of substantially tear-drop configuration to improve the appearance of the instrument by imparting a streamline aspect. The knob 60 is also preferably of substantially cup-shaped configuration internally and 20 co-operates with the sleeve in a relatively smooth manner to prevent access of dirt, moisture, and other foreign matter to the stem 52, which is substantially enclosed by the co-operation of the knob at the outer end of the sleeve 56. 25

A stem 52 is provided for each of the arms 59 and 79. A backing pin 54 likewise is provided for each of the arms 59 and 79, backing pins being mounted on the frame 23 each in position opposing the stems 52. Each backing pin comprises an elongated shell closed at one end and sliding in a shell-like casing 62, the closed end of the pin 54 extending in the chamber 49 in alignment with the opposing end of the stem 52. The casing 62 comprises an elongated preferably cylindrical shell closed at one end and threaded as at 64 in an opening formed in the frame 23 so that the open end of the shell 62 opens in the chamber 49. The hollow pin 54 and shell 62 co-operate to form an expandable casing in which is enclosed 40 a spring or other suitable resilient means 66 adapted to expand the casing provided by the hollow pin 54 and the shell 62 so that, the shell 62 being enclosed on the frame 23, the closed end of the pin is urged outwardly of the shell and 45 into the chamber 49 in position to yieldingly bear upon and press against the opposite side of the disk 61 or 81 with which it is associated opposite from the stem 52. Each of the arm-ending disks 61 and 81 therefore is held by and between the 50 facing ends of a stem 52 and a co-operating backing pin 54, the backing pin being normally urged by the spring to maintain the disk, with which it is associated, firmly against the opposing end of the stem. In order to adjust the position of 55 either arm 59 and 79 on the support frame 23, it is merely necessary to rotate the head 60 of the stem co-operatively associated with said arm in one direction or another in order to either advance the stem and push the end of the arm in 60 the chamber 49 against the yieldingly mounted backing pin or to retract the stem and permit the backing pin to maintain the end of the arm against the end of the retracted stem. It will be seen that the stem 52 and the backing pin 54 65 are enclosed in a dust-proof manner preventing deterioration of the operating parts, that the opposing ends of the stem and backing pin extend in the chamber 49, which is substantially enclosed save for the slot 51, through which the 70 adjusting arm 59 or 79, as the case may be, extends into the chamber.

The assembly is particularly attractive and neat in appearance, all operating parts being substantially enclosed not only to prevent access 75

thereto of foreign matter but also to prevent damage to the threads of the stem and to the backing pin by accidental impact upon these parts.

A preferably sheet metal cover 89 is secured 5 on the spider 75, said cover having flanged peripheral portions 91 fastened in any suitable fashion as by means of the studs 93 to the edges of the spider 75, the cover 89 enclosing the outwardly facing surface of the spider 75 and the 10 spider 85 is enclosed between the spider 75 and the cover 89. The cover 89 is formed with openings 95 in position to reveal portions of the circular edges of both spiders which are formed with scale-carrying surfaces 97 visible through 15 the openings 95.

It will be seen that the spider 85, since it is fastened on the frame 13 will tilt with the telescope while the spider 75, which is journaled on the axle of the flange may be held in adjusted 20 position with respect to the support by means of the arm 79. The surfaces of the spiders exposed through the openings 95 may be formed with suitable scales for indicating the angularity of the telescope and the vertical and horizontal 25 components of the angularity expressed in suitable terms as for instance in horizontal and vertical stadia distance constants, which may be determined directly by reading the scales when the telescope is in adjusted position. To this 30 end, one of the openings 95 may expose a surface of the spider 85 containing an angularity scale 99 and a co-operating portion of the spider 75 containing a gauge mark 101 and a vernier scale 103 so that the angularity of the telescope may 35 be determined on the scale 99 by means of the gauge mark 101 and the vernier scale 103. The other of the openings 95 likewise may expose a portion of the scale surface 97 of the spider 85 containing a scale 105 comprising horizontal stadia constants and a scale 107 of vertical stadia 40 constants, the scales 105 and 107 extending at opposite edges of the segmental scale surface 97, said opening also exposing a portion of the scale surface 97 carrying a gauge mark 109 in position to co-operate with the scale 107 in order to indicate the stadia constant determined by the sighting 45 position of the telescope. Means is or may be also provided affording a gauge mark 111 in position to co-operate with the scale 105 and visible 50 through the opening in order to indicate the horizontal stadia constant corresponding with the sighting position of the telescope. The gauge mark 111 is preferably formed on a suitable plate 113 secured on the inner surface of the cover 89 in any suitable fashion as by the holding screws 55 115, said plate having an edge disposed opposite the edge of the scale surface 97 containing the scale 105 and carrying the gauge mark 111 in position visible through the opening 95.

The spider 75 carries a spirit level 117 mounted thereon preferably along its upwardly facing substantially flat edge in order to permit the spider 75 to be accurately adjusted on the support pedestal by means of its tangent adjusting screws in 60 conditioning the instrument for use in a particular location. It will be understood that the plane table, on which the instrument is mounted for use, may not be exactly level, for which reason it is necessary to level the spider 75 before 65 sighting the telescope and making the stadia readings on the scales.

The spirit level 117 may be of any suitable or convenient form or construction and preferably comprises a housing 119 containing a vial 121 70 therein and support means comprising headed

stems 123, which penetrate the opposed ends of the vial housing 119 and are threaded at their lower end into the top of the spider 75, clamping nuts 125 are or may be provided on the stems 123 to secure the parts in mounted relationship. 5 By screwing the stems 123 to a proper distance in the frame 75, it is possible to adjust the vial in proper alignment on the spider, and I prefer to utilize a vial, housing, and adjustable mounting substantially as shown in my co-pending 10 application, Serial Number 751,241, filed November 2, 1934.

The telescope or sighting device 11 comprises a tubular, preferably cylindrical barrel 131, which is or may be provided with a bellied extension 15 133 at one end to receive an objective lens assembly 135. At its opposite end, the telescope barrel is provided with an eyepiece assembly 137 including an eyepiece focusing device 139 and an adjustable reticle 141. The barrel also carries 20 an objective focusing slide 143 between the eyepiece and objective lens assemblies. The objective slide carries a lens assembly 145 fitted therein and slidable longitudinally within the barrel for the purpose of focusing the telescope. The 25 objective slide comprises a preferably cylindrical sleeve having an aperture 147 in its end facing the eyepiece assembly and carries a frame 149 secured at its end opposite in the aperture 147 in any suitable fashion as by means of the 30 holding screws 151. The frame 149 carries the focusing lens 153 in alignment with the aperture 147.

Means having a portion 155 extending within and a preferably knurled collar portion 171 operable outwardly of the barrel of the telescope may be provided for adjusting the position of the slide 143 within the barrel of the telescope. The reticle also is adjustable in the barrel by means of screws 181 having heads exposed outwardly 35 of the barrel and normally enclosed by a readily removable cover 205. The eyepiece also has a turnable part 195 projecting from the cover 205 at the end of the telescope for focusing the eyepiece lens system on the cross hairs of the reticle; 40 and a scale 213 and index 215 may be arranged on the part 195 and the cover to indicate the 45 adjustment of the eyepiece.

The telescope or sighting device 11 also preferably carries a spirit level 217, preferably detachably mounted thereon, as by means of a removable support frame 225 demountably secured on seats provided on the telescope barrel by rings or collars 229 shrunk thereon, to facilitate leveling of the telescope, and any suitable or preferred means may be employed for securing the telescope barrel in the tilting support sleeve 13. 55

I do not herein claim the telescope or any of its details nor the arrangement shown for securing the telescope in the support sleeve 13, nor 60 the compass 31, nor the spirit levels 117 and 217, nor the means for mounting the said spirit levels, nor the tilting telescope support means 15, including the sleeve-like portion 13 thereof, since the same form the subject-matter of copending divisional applications.

It is thought that the invention and numerous of its attendant advantages will be understood from the foregoing description and it is obvious 70 that numerous changes may be made in the form, construction, and arrangement of the several parts of the illustrated apparatus without departing from the spirit or scope of my invention or sacrificing any of its attendant advan- 75

tages, the forms herein described being merely for the purpose of illustrating the invention.

Having thus described my invention, what I claim as new and desire to secure by Letters Patent is as follows:

1. A device of the class described, comprising a pair of frame elements interconnected for relative rotational movement, one of the elements forming a support for the other, and said other element carrying means forming a mounting for a sighting device, and means to adjust the angular relationship of the elements comprising chamber-forming means on said support providing an enclosing chamber having a lateral opening, means on said mounting element comprising a finger in position extending in said chamber through said opening and having a bearing portion within said chamber, and adjusting means on said chamber-forming means and cooperatively associated with said bearing portion within the chamber for shifting said finger therein to adjust the relative angular relationship of the said frame elements.

2. A device of the class described comprising a support frame having a pair of enclosed chambers, a sighting device tilttable on the frame, scale means comprising a member shifttable with the sighting device and a co-operating member adjustable with respect to the frame, means to adjust said co-operating device with respect to said frame comprising an arm connected to the sighting device and extending in one of said chambers, an arm connected on the co-operating member and extending in the other of said chambers, adjusting means for each of said arms comprising means on the frame co-operatively associated with its associated arm within the chamber in which said arm extends whereby to shift the same with respect to the frame.

3. A device of the class described comprising a support frame, means for mounting a sighting device for relative angular movement on the frame, scale means comprising a member carried by and shifttable with the sighting device, and a co-operating member adjustable with respect to the frame, said members having adjacently extending surfaces carrying scale means whereby the relative angular position of the sighting device with respect to the frame may be determined, and a cover fast with the co-operating member and positioned to enclose said scales and protect the same.

4. A device of the class described comprising a support frame, a sighting device turnable on the frame, scale means comprising a member carried by and shifttable with the sighting device, and a co-operating member adjustable with respect to the frame, said members having adjacently extending surfaces carrying scale means whereby the inclination of the sighting device with respect to the horizontal may be determined, a cover fast with the co-operating member and positioned to enclose said scales and protect the same, said sighting device being mounted for tilting movement on an axle and one of the scale members comprising a segmental spider fixed on said axle, said co-operating scale member comprising a spider journaled on said axle adjacent the fixed spider, the cover member being carried by one of said spiders and enclosing the other and being formed with openings in position to expose the scale-carrying surfaces of both spiders, said cover member also carrying a gauge mark thereon in position to cooperate with a scale formed on the journalled spider.

5. A device of the class described comprising a frame having a pair of enclosed chambers, means for mounting a sighting device for relative angular movement on the frame, scale means comprising a member shifttable with the sighting device, and a cooperating member adjustable with respect to the frame, means to adjust said cooperating device with respect to said frame comprising an arm connected to the sighting device and extending in one of said chambers, means to drivingly clamp said arm on said sighting device, another arm connected on the cooperating device and extending in the other of said chambers, spirit level means mounted on said cooperating member, and adjusting means for each of said arms comprising means on the frame and cooperatively associated with said arms within the chambers whereby to shift the same with respect to the frame.

6. A device of the class described comprising a frame element formed with a bearing for the reception of an axle, an axle in said bearing, a sighting device carried by said axle, said frame comprising a pair of spaced legs extending from said bearing and an integral frame portion interconnecting said spaced legs and forming a chamber having an opening between said legs, means on said axle comprising a finger extending through said chamber opening and having a bearing portion within the chamber, a stem threaded in a wall of said chamber and having a portion extending in said chamber in position to engage one side of said bearing portion, means extending outwardly of said chamber and manually operable to turn said stem, means carried on the walls of said chamber and having a presser portion extending in said chamber on the opposite side of said bearing portion, and means yieldingly urging said presser portion toward the bearing portion whereby to hold the same in engagement with said stem so that by adjusting the stem the relative angular position of said arm with respect to said frame about the axis of said shaft may be critically adjusted.

7. A device of the class described comprising a support frame, a sighting device turnable on the frame, scale means comprising a member carried by and shifttable with the sighting device, and a co-operating member adjustable with respect to the frame, said members having adjacently extending surfaces carrying scale means whereby the inclination of the sighting device with respect to the horizontal may be determined, a cover fast with the co-operating member and positioned to enclose said scales and protect the same, the sighting device being mounted for tilting movement on an axle and one of the scale members comprising a segmental spider fixed on said axle, the co-operating scale member comprising a segmental spider journaled on said axle adjacent the other spider, said cover member being carried by one of said spiders and enclosing the other, and said cover member being formed with openings in position to expose the scale-carrying surfaces of both spiders.

8. A device of the class described comprising a frame element formed with a bearing for receiving an axle, an axle in said bearing, means mounting a sighting device for rotation with said axle, means on said axle comprising a projecting element, means on said frame element forming a chamber having an opening and the projecting element having a finger portion extending into the chamber through said opening and having a bearing portion disposed within the chamber, a stem threaded in a wall of said chamber at one

end thereof in position to engage one side of said bearing portion, means extending outwardly of said chamber and manually operable to turn said stem, means in the walls of said chamber at the 5 opposite end thereof and having a presser portion extending in said chamber on the opposite side of said bearing portion, and means yieldingly

urging said presser portion toward the bearing portion whereby to hold the same in engagement with said stem so that by adjusting the stem the relative angular position of said finger about the axis of said axle with respect to the element having the chamber may be critically adjusted. 5

ADOLPH LANGSNER.
